DRAW BOLT LOCK

Wallace E. Atkinson, Petersburg, Va., assignor to Long Manufacturing Company, Inc., Petersburg, Va., a corporation of Virginia

Application May 24, 1955, Serial No. 36,193

Term of patent 14 years

(Cl. D50—7)

Fig. 1.

Fig. 2.

Fig. 3.

Fig. 4.

Fig. 5.

Fig. 1 is a perspective view of a draw bolt lock, in closed condition, showing my new design.

Fig. 2 is a similar perspective view as viewed from the opposite side.

Fig. 3 is a perspective view with the draw bolt lock shown in open condition.

Fig. 4 is a side elevational view thereof.

Fig. 5 is an end elevational view opposite the lock-supporting end.

I claim:

The ornamental design for a draw bolt lock, as shown.
